UNITED STATES PATENT OFFICE.

JOHN B. PAYNE, OF LEXINGTON, KENTUCKY.

DESIGN FOR A BADGE.

SPECIFICATION forming part of Design No. 23,961, dated January 29, 1895.

Application filed November 22, 1894. Serial No. 529,651. Term of patent 7 years.

To all whom it may concern:

Be it known that I, JOHN B. PAYNE, a citizen of the United States, residing at Lexington, in the county of Fayette and State of Kentucky, have invented or produced a new and original Design for Badges, of which the following is a specification.

This design has for its object to provide a novel and ornamental badge which presents a characteristic and handsome appearance to the eye, and the leading feature thereof consists in a circular badge having on its face a representation of a hand printing press, a printer's composing stick, and a printer's type case.

The invention is illustrated by the accompanying drawings, in which—

Figure 1 is a face view of the badge; and Fig. 2 is a cross sectional view of the same.

In the drawings the numeral 1 indicates the badge which is circular or in the form of a disk and bears on its face a representation of the section of a terrestrial globe, as at 2. Above the representation of the section of the terrestrial globe is arranged the pictorial representation of a hand printing-press, as at

3, and at one side of the same is represented a hand, as at 4, grasping a printer's composing-stick, as at 5, while at the opposite side of the press is placed a stand, as at 6, supporting a printer's type-case, as at 7, with a compositor standing in front of the case and represented as composing type. Above the representation of the hand printing-press are arranged a shooting-stick 8 and a mallet 9. The section of the terrestrial globe is divided into spaces by curved crossing lines, and some of the spaces are adapted to receive an inscription.

The design provides a badge or button-head which presents a characteristic, handsome, and ornamental appearance.

What I claim is—

The design for a circular badge, substantially as shown and described.

In testimony whereof I have hereunto set my hand in presence of two subscribing witnesses.

JOHN B. PAYNE.
